UNITED STATES PATENT OFFICE.

SEWALL CABOT, OF BROOKLINE, MASSACHUSETTS, ASSIGNOR TO STONE TELEGRAPH AND TELEPHONE COMPANY, A CORPORATION OF MAINE.

SPACE TELEGRAPHY.

No. 908,742.

Specification of Letters Patent.

Patented Jan. 5, 1909.

Application filed March 18, 1907. Serial No. 362,818.

To all whom it may concern:

Be it known that I, SEWALL CABOT, a citizen of the United States, and a resident of Brookline, in the county of Norfolk and 5 State of Massachusetts, have invented a new and useful Improvement in Space Telegraphy, of which the following is a specification.

My invention relates to space telegraph transmitting systems.

10 The object of my invention is to increase the power factor of the primary power circuit of a space telegraph transmitting system, and to prevent arcing at the spark gap of the sonorous circuit of said system, thereby permitting an increase in the spark-frequency of the electrical oscillations developed in said sonorous circuit without causing the detrimental effects produced by the formation of electric arcs at said spark gap.

15 Referring to the drawings which accompany and form a part of this specification, Figure 1 represents conventionally a system of circuits embodying my invention, and Fig. 2 represents in diagrammatic form one 25 of the arrangements of circuits and apparatus in which I have embodied said principle in actual practice.

In the figures, A represents a source of vibratory electromotive force; K K' are keys; 30 M M' are transformers of which the primary and secondary windings respectively are I_1 , I_1' and I_2 , I_2' ; L L' are inductances; C C' C'' are condensers; V is an elevated conductor earthed at E.

35 While, as shown in Fig. 1, I may employ the usual key K in the primary circuit of the generator A, I prefer, as shown in Fig. 2, to employ a key or circuit controller consisting of a number of contact members 1, 2, connected in both sides of the intermediate circuit which connects the sonorous circuit S C I₁ with the primary power circuit A I₁'. One set of contact members 1 is fixed and the other set which is supported by the rod 3 is 40 adapted to be moved into contact with the stationary set 1 by means of the key K'.

I have successfully operated a wireless telegraph system as shown in Fig. 2 by employing inductances and capacities having the 45 following values, viz: coil L, 50 henries; coil L', 50 henries; condenser C', .02 microfarads; condenser C'', .0025 microfarads; condenser C, .04 microfarads; frequency of alternating-current-generator A, 60 cycles. I have 50 found that when the said coils and condensers

are given the values above set forth, the power factor of the primary power circuit is unity and sparking takes place at S without the accompaniment of an electric arc.

It will be understood of course that the 60 values above given for the capacities and inductances of the coils and condensers are merely by way of example, for obviously said values may be greatly varied even with currents of a given frequency in the primary 65 power circuit.

The adjustments of the several coils and condensers above mentioned are best determined empirically in the following manner: Measure the power in the primary power circuit by means of a watt meter and adjust the constants of the coil or coils L L' and the condenser or condensers C' C'' until the apparent watts as measured by said watt meter 70 are equal to the product of the voltage 75 across the primary I_1' multiplied by the current in the primary power circuit. Inasmuch as the reactance of the primary power circuit when isolated is an inductance reactance, it follows that the electromagnetic 80 constants of the circuit including the secondary I_2' must be such that the reaction of said secondary on the said primary is a capacity reaction of such value as to reduce the reactance of the primary power circuit to 85 zero,—in other words, to render the load on the generator a non-inductive load.

It will be obvious to those skilled in the art that the power factor of the primary power circuit may be rendered unity in a variety of ways, and therefore I do not desire to be limited to the particular arrangement shown in the drawings. When the constants of the intermediate circuit are so adjusted as to increase the power factor of the 90 power circuit to unity, the intermediate circuit offers very little impedance to the passage of currents from the generator A to the sonorous circuit S C I₁ during the charging period of the condenser C; but as soon as 95 said condenser discharges across the gap S, the coils L L' retard the flow of current in said intermediate circuit and thereby prevent the formation of an arc across the gap S.

The intermediate circuit may be grounded 100 at E' E'' if desired as shown in Fig. 2.

I claim,

1. A space telegraph transmitting system comprising a sonorous circuit, a power circuit including the primary of a transformer, 110

an intermediate circuit connected with said sonorous circuit and including the secondary of said transformer, and means associated with said intermediate circuit for increasing 5 the power factor of said power circuit.

2. A space telegraph transmitting system comprising a sonorous circuit, a power circuit including the primary of a transformer, an intermediate circuit connected with said 10 sonorous circuit and including the secondary of said transformer, and means associated with said intermediate circuit for rendering the power factor of said power circuit unity.

3. A space telegraph transmitting system 15 comprising a sonorous circuit, a power circuit including the primary of a transformer, an intermediate circuit connected with said sonorous circuit and including the secondary of said transformer, and a condenser associated with said intermediate circuit and so 20 constructed and arranged as to increase the power factor of said power circuit.

4. A space telegraph transmitting system comprising a sonorous circuit, a power circuit including the primary of a transformer, an intermediate circuit connected with said sonorous circuit and including the secondary of said transformer, and a condenser connected across said intermediate circuit and 25 so proportioned as to increase the power factor of said power circuit.

5. A space telegraph transmitting system comprising a sonorous circuit, a power circuit including the primary of a transformer, an intermediate circuit connected with said sonorous circuit and including the secondary of said transformer, a circuit controller in 35 said intermediate circuit and condensers connected across said intermediate circuit, one on either side of said circuit controller, said condensers being so adjusted as to increase 40 the power factor of said power circuit.

6. A space telegraph transmitting system comprising a sonorous circuit, a power circuit including the primary of a transformer, an intermediate circuit connected with said sonorous circuit and including the secondary of said transformer, a circuit controller constructed and arranged to open said intermediate circuit at two points, and condensers 50 connected across said intermediate circuit, one on either side of said circuit controller, said condensers being so adjusted as to increase the power factor of said power circuit.

55 7. A space telegraph transmitting system comprising a sonorous circuit, a power circuit including the primary of a transformer, an intermediate circuit connected with said sonorous circuit and including the secondary 60 of said transformer, an inductance included in said intermediate circuit, and means associated with said intermediate circuit constructed and arranged to increase the power factor of said power circuit and to counteract 65 in full or in part the reactance of the afore-

said inductance during the charging period of said sonorous circuit, said inductance being so proportioned that during the discharging period of said sonorous circuit said inductance sufficiently retards the flow of current in 70 said intermediate circuit to prevent the formation of an arc across the gap of the sonorous circuit.

8. A space telegraph transmitting system comprising a sonorous circuit, a power circuit including the primary of a transformer, an intermediate circuit connected with said sonorous circuit and including the secondary of said transformer, a coil having very large 75 inductance connected in series with said intermediate circuit, and a condenser connected across said intermediate circuit, said condenser being so proportioned as to increase the power factor of said power circuit and to reduce the reactance offered by said 80 intermediate circuit to the currents delivered thereto by said power circuit during the charging period of said sonorous circuit.

9. A space telegraph transmitting system comprising a sonorous circuit, a power circuit including the primary of a transformer, an intermediate circuit connected with said sonorous circuit and including the secondary of said transformer, a coil having very large 90 inductance connected in series with said intermediate circuit, said coil being so proportioned that during the discharging period of said sonorous circuit said coil sufficiently retards the flow of current in said intermediate circuit to prevent the formation of an 95 arc across the gap of said sonorous circuit, and a condenser connected across said intermediate circuit.

10. A space telegraph transmitting system comprising a sonorous circuit, a power circuit including the primary of a transformer, an intermediate circuit connected with said sonorous circuit and including the secondary of said transformer, a circuit controller in 105 said intermediate circuit, and a condenser connected across said intermediate circuit, said condenser being so proportioned as to increase the power factor of said power circuit.

11. A space telegraph transmitting system comprising a sonorous circuit, a circuit including the primary of a transformer, an intermediate circuit connected with said sonorous circuit and including the secondary of said transformer, a circuit controller constructed and arranged to open said intermediate circuit at two points, and a condenser connected across said intermediate circuit, said condenser being so proportioned 115 as to increase the power factor of said power circuit.

12. A space telegraph transmitting system comprising a sonorous circuit, a power circuit including the primary of a transformer, an intermediate circuit connected with said sonorous circuit and including the secondary 120 125

of said transformer, and a condenser associated with said intermediate circuit and so constructed and arranged as to render the power factor of said power circuit unity.

5 13. A space telegraph transmitting system comprising a sonorous circuit, a power circuit including the primary of a transformer, an intermediate circuit connected with said sonorous circuit and including the secondary 10 of said transformer, and a condenser connected across said intermediate circuit and so proportioned as to render the power factor of said power circuit unity.

14. A space telegraph transmitting system 15 comprising a sonorous circuit, a power circuit including the primary of a transformer, an intermediate circuit connected with said sonorous circuit and including the secondary of said transformer, an inductance included 20 in said intermediate circuit, and means associated with said intermediate circuit for increasing the power factor of said power circuit.

15. A space telegraph transmitting system comprising a sonorous circuit, a power circuit 25 including the primary of a transformer, an intermediate circuit connected with said sonorous circuit and including the secondary of said transformer, an inductance included 30 in said intermediate circuit, and means associated with said intermediate circuit for

rendering the power factor of said power circuit unity.

16. A space telegraph transmitting system comprising a sonorous circuit, a power circuit including the primary of a transformer, 35 an intermediate circuit connected with said sonorous circuit and including the secondary of said transformer, an inductance included in said intermediate circuit, and a condenser associated with said intermediate circuit and 40 so constructed and arranged as to increase the power factor of said power circuit.

17. A space telegraph transmitting system comprising a sonorous circuit, a power circuit including the primary of a transformer, 45 an intermediate circuit connected with said sonorous circuit and including the secondary of said transformer, an inductance included in said intermediate circuit, and a condenser connected across said intermediate circuit 50 and so proportioned as to increase the power factor of said power circuit.

In testimony whereof, I have hereunto subscribed my name this 13th day of March 1907.

SEWALL CABOT.
